The ornamental design for a wheel for an automobile thereof as shown and described.

DESCRIPTION

FIG. 1 is a perspective view of a wheel for an automobile thereof, showing our new design;

FIG. 2 is a second perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a partial front perspective view thereof.

The portions of the drawings that are shown as relatively lighter toned, depict portions of the wheel for an automobile that form no part of the claimed design.
